UNITED STATES PATENT OFFICE.

ALBERT B. WEISSENBORN, OF APPLETON, WISCONSIN.

LAY-MOTION FOR LOOMS.

No. 811,012.

Specification of Letters Patent.

Patented Jan. 30, 1906.

Application filed June 3, 1905. Serial No. 263,574.

To all whom it may concern:

Be it known that I, ALBERT B. WEISSENBORN, residing in Appleton, in the county of Outagamie and State of Wisconsin, have invented new and useful Improvements in Lay-Motions for Looms, of which the following is a description, reference being had to the accompanying drawings, which are a part of this specification.

10 This invention relates to lay-motions for looms, and has for its object to provide electrically-controlled fluid-pressure means for moving the lay and retaining it at the dwell at the will of the weaver.

15 Another object of this invention is to provide for limiting the throw of the lay with an adjustable cushioning means.

In hand-loom for weaving wire fabric of considerable width, such as one hundred inches and wider, the proper operation of the lay requires the presence of a third operative in addition to the two weavers at the ends of the loom, whose duty is to assist the weavers in throwing the lay. The present invention is 25 designed to dispense with the services of the third operative and render the operation of the lay by the weavers less burdensome and more accurate.

The above objects are accomplished by 30 means of a fluid-pressure cylinder having a piston connected to the lay, preferably midway between the ends thereof, for throwing the lay with power, the supply of pressure fluid to the cylinder being controlled by an 35 electrical system whose contacts or circuit-closers are located upon the lay-cap in position to be naturally closed by the usual manipulation of the lay by the weavers. In addition to the above a means is provided for also applying power to the lay during its forward 40 movement, which comprises an adjustable spring by which the force of the blow struck upon the weft-wire by the reed of the lay may be controlled. Also in connection with the 45 above is preferably provided a cushioning means for limiting the throw of the lay, such as a dash-pot adapted to adjustably determine the limit of movement of the throw of the lay and adapted to have its cushioning effect increased or diminished at will.

With the above and other objects in view the invention consists in the devices and parts and combinations thereof as herein set forth and their equivalents.

55 Referring to the accompanying drawings, in which like characters of reference indicate

the same parts in the several views, Figure 1 is an end elevation of a loom provided with the lay-motion devices of this invention, the electrical valve-controlling circuits being 60 shown in diagram. Fig. 2 is a side elevation of the pressure-cylinder with its valves and connections, parts being broken away to illustrate the valve construction. Fig. 3 is a plan view thereof with the lay connections, 65 the cylinder being broken away to disclose the passage between it and the valve mechanism. Fig. 4 is an end elevation of these parts. Fig. 5 is a plan view of one end of the lay-cap, illustrating the position and arrangement of the push-buttons. Fig. 6 is an end elevation of the lay-cap, partly sectioned to show the construction of the push-buttons; and Fig. 7 is a side elevation of the lay limiting and cushioning means.

In the drawings, 10 represents an ordinary hand-loom, such as is now generally used for wire-weaving, and 11 is the lay thereof, having the usual lay-cap 12. The lay as usually constructed is provided with a downwardly-extending flange 13 along its bottom, and to the rear face of this flange I connect a cleat 14, having a vertical opening therethrough, into which is pivotally fitted the upper end of a bolt 15, with a pin 16 riding in a radial slot of the cleat to form a swivel connection for the bolt. The lower end of the bolt 15 is provided with a sleeve 17 to receive the end of a stud 18, which serves as a connecting means between the lay and the piston-rod 19 of the pressure-cylinder 20 and the connecting-rod 21 of the spring-actuated driving mechanism, to be later described. The stud 18 has a head on one end to form a thrust-bearing for the sleeve end of connecting-rod 21, which is pivotally mounted on said stud and is confined in position by a cotter-pin 22, passing through the stud. Beyond the cotter-pin 22 the stud is first squared to form a wrench-hold 23. Then it is threaded 100 and then reduced, so that one member of the forked end of the piston-rod 19 may be threaded on said threaded portion against the wrench-hold 23, and the other member of the forked end may fit upon the reduced portion and be 105 locked thereto by a cotter-pin 24, the sleeve 17 of the swiveled bolt being pivotally mounted on the stud between said forked members.

The fluid-pressure cylinder 20 is closed at the front end in the usual manner; but the rear end is open to the atmosphere, there being an elbow or deflecting-hood 25 connected

thereto to prevent the piston of the cylinder throwing lubricating-oil upon the warp-beam behind. The cylinder is provided on one side with a projecting-headed boss forming a horizontal trunnion 26, which is pivotally mounted in a bearing 27, having a downwardly-extending stem 28, which in turn is pivotally mounted in a vertical clamp-bearing 29 on the upper end of a standard 30, rigidly supported on the floor in any desirable manner.

The pivotal connection of the piston-rod 19 with the stud 18 and the pivotal connection between the trunnion 26 of the cylinder and its support permits the arc of swing of the lay 11 without binding the piston-rod with the cylinder, and the swivel connection between the bolt 15 and the cleat 14 and the swivel connection between the stem of the bearing 20 and the standard permits of the slight longitudinal movement of the lay which is sometimes occasioned in dressing the loom without bending the piston-rod or otherwise damaging the mechanism.

The front end of the cylinder 20 has a passage-way 31, connecting it with a valve mechanism 32, comprising an inlet-valve 33 and an outlet-valve 34, the former communicating with a fluid-pressure chamber 35, having a flexible tubing 36 connected thereto and carrying compressed air or other pressure fluid from some suitable source of supply (not shown) and the latter communicating with the atmosphere through a discharge-outlet 37. The inlet and outlet valves 33 and 34, respectively, are similar in construction, being in the form of conical valve members mounted upon valve-stems 38 and 39, which slide in the walls of the casing of the valve mechanism and into hollow screw-plugs 40, containing coil-springs 41, to press the valve-stems rearwardly and hold the valve members on correspondingly-shaped valve-seats in the walls of the passage-way 31. The inlet-valve 33 is so arranged that the pressure of the air in the pressure-chamber 35 tends to hold it closed, and the outlet-valve 34 is so arranged that the pressure of the air within the cylinder tends to hold it closed.

A lever 42 is pivotally mounted upon a stud 43 midway between the exposed rear ends of the valve-stems 38 and 39 and is connected, by means of a link 44, with an armature-lever 45, which is pivoted to an overhanging member of a magnet-frame 46, whose magnet-coils 47 are adapted to attract the armature-lever and cause it to swing the lever 42. A rod 48 is threaded through the lower end of the magnet-frame 46, being locked in adjustable position by a jam-nut 49, and passes through a slot 50 in the lower end of the armature-lever 45, with a cross-pin 51 therethrough to engage the armature-lever and limit its movement away from the magnet. A coil-spring 52, surrounding said rod 48 and bearing upon a nut 53, threaded thereon, forces the armature-

lever against the stop-pin 51 when said armature-lever is not attracted by the magnet. When the magnet is not energized, the force of the spring 52 is sufficient to hold the armature-lever 45 against the stop-pin 51, so that the lever 42 presses against the valve-stem 39 and holds the outlet-valve 34 open against the pressure of its spring 41, the valve-stem 38 being out of engagement with the lever 42 and held closed by its spring 41 and the pressure of air in the pressure-chamber 35. When the magnet 47 is energized, it attracts the armature-lever 45 and swings it against the pressure of spring 52 to cause the lever 42 to also swing and engage the valve-stem 38 and force the inlet-valve 33 off of its seat against the action of its spring 41, the outlet-valve being permitted to close by the assistance of its spring 41, since its stem 39 is released by the lever 42. From the foregoing it will be understood that when the magnet is energized the inlet-valve is held open to admit air-pressure to the cylinder 20, while the outlet-valve is closed, so that the air-pressure may operate upon the piston and cause it to swing the lay rearwardly, and when the magnet is deenergized the inlet-valve is closed and the outlet-valve is opened to allow of the exhaust of the air within the cylinder, and thereby permit the lay to swing forwardly. The magnet 47 is preferably of comparatively high resistance, so that it may be connected to an electric-lighting circuit of about one hundred and ten volts with a relay-switch for making and breaking its circuit, the magnet of said relay being included in a battery-circuit which may be closed by one or more push-buttons in convenient access to the weavers. As here shown in diagram in Fig. 1, the lighting-circuit, including the magnet 47, is represented by the wires 54 with a relay-switch 55, the magnet 56 of said relay-switch being included in the battery-circuit represented by wires 57, which preferably extend to the ceiling and then to the lay, where they connect with a plurality of push-buttons arranged in multiple arc. The closing of any push-button will complete the battery-circuit to energize the relay-magnet 56 and cause it to close the relay-switch 55 and complete the circuit through the magnet 47 to charge the cylinder, while the release of such push-button will open the battery-circuit and cause the relay-switch to open the circuit of magnet 47 and discharge the cylinder. The push-buttons are preferably arranged with four or five in line on each end of the lay-cap 12, at the upper front rounded corner thereof, where the weavers usually place their hands in swinging the lay back and forth. An arrangement which I have found effective in practice is to cut away this upper front rounded corner of the lay-cap, as at 58, and restore the curved contour thereof by means of a curved metallic shell or plate 59, which has

riveted to it a series of spring-strips 60, carrying the buttons or knobs 61 on their free ends and pressing them outwardly through openings in the metal shell 59. A strip of insulating material 62 is connected to the under side of the metal shell 59 and has mounted on it a series of parallel oblique spring-strips 63, with their free ends extending just beneath the free ends of the spring-strips 60, so that when the buttons 61 are pressed inwardly the strips 60 contact with the strips 63 and complete the battery-circuit, since one of the wires 57 is connected to the metal shell and the other is connected to each of the spring-strips 63. The push-buttons are provided in numbers at each end of the lay-cap to be available for the purpose intended when the loom is arranged for weaving narrower or wider fabric, since the position of the weaver's hand on the lay-cap is nearer to or farther from the middle thereof as the fabric being woven is narrower or wider. This change of position of the weaver's hand on the lay-cap is required by reason of the fact that while he holds the lay-cap with one hand he receives and returns the shuttle with the other hand, and if the hand on the lay-cap should remain in the same position for weaving narrower fabric as for weaving wider fabric it would be necessary for the weaver to cross his arms to receive and return the shuttle, which would be very inconvenient, if not impossible.

The connecting-rod 21, before referred to, is pivoted at its rear end to the upper end of a rock-lever 64, which is pivoted on an outstanding arm 65 of the standard 30 and has a coil-spring 66 connected to its lower end. The coil-spring 66 is adjustably mounted at its rear end, preferably by means of a crank-screw 67, which is threaded through a bracket 68 on the floor with a jam-nut 69 thereon to hold it in its adjustments. The tendency of the spring 66 is to cause the rock-lever 64 to swing the lay forwardly by means of the connecting-rod 21, and this tendency may be increased or diminished by altering the adjustment of the screw-crank 67, so that the weft-wire may be struck with the proper force by the reed of the lay. A coil-spring 70 connects the rear end of the cylinder 20 with the arm 65 to counterbalance the weight of the valve mechanism and other parts on the front end thereof.

A dash-pot for cushioning the rearward stroke or throw of the lay is provided and comprises a cylinder 71, mounted on the standard 30, with a piston therein having its stem 72 projecting through both heads of the cylinder, the lower end extending to a position where it is adapted to be engaged and forced upwardly by means of an arm 73 on the rock-lever 64 and the upper end being adapted to engage with an adjustable set-screw 74, threaded in a boss on the standard above the cylinder. The lower head of the cylinder is open.

to the atmosphere; but the upper head thereof is closed, with a T-coupling 75 connecting a petcock 76 and a check-valve 77 with the cylinder, so that the upward movement of the piston may be cushioned and retarded by the slow exit of air through the petcock and may be allowed to freely drop of its own weight by drawing in air through the check-valve. The action of the limiting and retarding device is to cushion the end of the rearward stroke of the lay which is produced by the action of the air in the cylinder 20 when a push-button is pressed and then limit it at a certain point determined by the engagement of the piston-rod 72 with the set-screw 74. The following forward movement of the lay effected by the action of the spring 66 is not influenced by the retarding mechanism, since the arm 73 leaves the piston-rod 72 to drop of its own accord. By adjusting the set-screw 74 the position at which the piston-rod 72 is stopped, and therefore the position at which the lay is stopped in its rearward movement, may be adjusted to suit the requirements.

In operation the weavers need only perform the same action which they at present perform with looms not provided with the improvements constituting this invention; but when they press their hands upon the lay-cap to force it rearwardly they close the battery-circuit by means of the push-buttons and complete the circuit through the magnet 47 to admit compressed air to the cylinder 20. This will force the lay rearwardly without their using great muscular effort, as at present, and should it be desired to prolong the dwell of the lay for any reason they have only to keep their hands upon the push-buttons and the air-pressure in the cylinder will continue to hold the lay at the dwell until said push-buttons are released, when the air in the cylinder is permitted to freely exhaust and the spring 66 produces the forward stroke of the lay. As the point of dwell of the lay is determined by the limiting device and is therefore the same with each successive operation and the force with which the lay is thrown forward by means of the spring 66 is also constant with each successive operation, the effect produced by the lay upon the work will always be the same, and consequently the fabric will be more uniform in texture than when these influences depend upon the manual operation by the weavers. It is obvious that the weavers are at the same time relieved almost entirely of their present exhaustive efforts in swinging the heavy lay back and forth throughout the weaving operation, though having it under more perfect control.

The invention is not confined to the specific details of construction here illustrated and described for the purpose of its exemplification, but is susceptible to various alterations and substitutions of parts without departing from its spirit and scope. Among the most obvi-

ous alterations of this nature are the omission of the relay-switch, so as control the circuit of the magnet 47 by means of the push-buttons direct, the connection of the spring-retarding means for the lay to the piston direct, and also the forming of the cushioning and limiting means by the piston of the cylinder 20.

What I claim as my invention is—

1. A lay-motion for looms, comprising a fluid-pressure lay-moving device, and electrical controlling means therefor with its circuit-closer located within free access of the weaver.

2. A lay-motion for looms, comprising a fluid-pressure lay-moving device, and electrical controlling means therefor with its circuit-closer located on the lay-cap of the loom.

3. A lay-motion for looms, comprising a fluid-pressure lay-moving device, and electrical controlling means therefor with its circuit-closer formed by a series of push-buttons on the lay-cap of the loom at different distances from the middle thereof.

4. A lay-motion for looms, comprising a fluid-pressure lay-moving device, and electrical controlling means therefor with its circuit-closer formed of a push-button at each end of the lay-cap of the loom.

5. A lay-motion for looms, comprising a fluid-pressure lay-moving device, and electrical controlling means therefor with its circuit-closer operated by the pressure of the weaver's hand in the usual manipulation of the lay-cap for producing the hand operation of the lay.

6. A lay-motion for looms, comprising a fluid-pressure lay-moving device, fluid-pressure-controlling valves therefor, an electrical valve-operating means, and an electrical controlling-circuit for said valve-operating means having its circuit-closer located on the lay in convenient access to the weaver.

7. A lay-motion for looms, comprising a fluid-pressure lay-moving device, an electrical controlling means therefor having its circuit-closer located in convenient access to the weaver, and a spring lay-moving device opposing the action of the fluid-pressure lay-moving device and adapted to move the lay in the opposite direction to the movement of the lay produced by said fluid-pressure lay-moving device.

8. A lay-motion for looms, comprising a fluid-pressure lay-moving device adapted to produce the rearward movement of the lay, an electrical controlling means therefor having its circuit-closer located in convenient access to the weaver, and a spring lay-moving device adapted to produce the forward movement of the lay.

9. A lay-motion for looms, comprising a fluid-pressure lay-moving device, valves controlling the admission and exhaust of pressure fluid thereof, a lever for actuating said valves, a magnet adapted to cause the move-

ment of the lever, and an electrical controlling-circuit for said magnet having its circuit-closer located in convenient access to the weaver.

10. A lay-motion for looms, comprising a fluid-pressure lay-moving device, pressure-fluid supply and exhaust valves therefor, said valves having exposed valve-stems, a lever pivotally mounted between said valve-stems and adapted when swung in one direction to open the supply-valve and permit the exhaust-valve to close and when swung in the other direction to open the exhaust-valve and permit the supply-valve to close, a magnet for producing the swinging movements of the lever, and an electrical controlling-circuit for said magnet having its circuit-closer located in convenient access to the weaver.

11. A lay-motion for looms, comprising a pressure-fluid lay-moving device formed by a suitably-mounted cylinder with a piston having connection with the lay, said cylinder having a passage-way in connection therewith, a spring-pressed slidably-mounted valve-stem carrying a pressure-fluid-supply valve for the passage-way, a spring-pressed slidably-mounted valve-stem carrying an exhaust-valve for the passage-way, said valve-stems having exposed ends, a lever pivotally mounted between the exposed ends of the valve-stems and adapted when swung in one direction to engage one valve-stem and open the supply-valve thereby and when swung in another direction to engage the other valve-stem and open the exhaust-valve thereby, a magnet for producing the swinging movements of the lever, and an electrical controlling-circuit for the magnet having its circuit-closer located in convenient access to the weaver.

12. A lay-motion for looms, comprising a fluid-pressure lay-moving device, a pressure-fluid supply and exhaust valve mechanism therefor having exposed valve-stems, a valve-lever pivotally mounted between the exposed valve-stems and adapted to engage one or the other thereof as it is moved in one direction or the other, a magnet-frame, a magnet mounted thereon, an armature-lever pivoted to the magnet-frame and having connection with the valve-lever, whereby the attraction of the armature-lever will cause the valve-lever to move in one direction, a bar adjustably mounted on the magnet-frame and passing through the armature-lever, a stop on the bar for limiting the movement of the armature-lever away from the magnet, and a coil-spring surrounding the bar and bearing on the armature-lever to force said armature-lever away from the magnet when the magnet is deenergized and thereby produce a movement of the valve-lever in the other direction, and an electrical controlling-circuit for the magnet having its circuit-closer in convenient access to the weaver.

13. A lay-motion for looms, comprising a pressure-fluid lay-moving device, consisting of a fluid-pressure cylinder having a pivotal support, a piston operating in the cylinder and having a pivotal connection with the lay, and a controlling system for the supply and exhaust of pressure fluid of the cylinder having its operating means located in convenient access to the weaver.
14. A lay-motion for looms, comprising a standard, a bearing having a pivotal support on the standard, a fluid-pressure cylinder having a trunnion pivotally mounted in the bearing, a piston operating in the cylinder, a bolt to which the piston is pivotally connected, said bolt having a pivotal connection with the lay, and an electrically-controlled pressure-fluid valve mechanism for the cylinder having its circuit-closer in convenient access to the weaver.
15. A lay-motion for looms, comprising a standard, a fluid-pressure cylinder pivotally mounted thereon, a piston operating in the cylinder and having connection with the lay, an electrically-controlled valve mechanism on the cylinder having its circuit-closer located within convenient access to the weaver, and a spring connecting the cylinder with the standard to counterbalance the weight of the valve mechanism.
16. A lay-motion for looms, comprising a suitable pivotally-mounted fluid-pressure cylinder, a piston operating therein, a stud to which the piston-rod is connected, a bolt pivotally mounted on the stud, and a cleat connected to the lay and having a swivel connection with the bolt.
17. A lay-motion for looms, comprising a suitable pivotally-mounted fluid-pressure cylinder, a piston operating therein, a stud to which the piston-rod is connected, a bolt pivotally mounted on the stud, a cleat connected to the lay and having a swivel connection with the bolt, a connecting-rod pivotally mounted on the stud, and a spring-operated lay-moving mechanism connected to the connecting-rod.
18. A lay-motion for looms, comprising a standard, a fluid-pressure cylinder pivotally mounted thereon, a piston operating in the cylinder and having a piston-rod with a forked end, a stud connected to the forked end of the piston-rod, a bolt pivotally mounted on the stud between the fork members of the end of the piston-rod, a cleat on the lay having a swivel connection with the bolt, a connecting-rod pivoted to the stud, a rock-lever pivotally mounted on the standard and connected to the connecting-rod, and an adjustable spring connected to the rock-lever.
19. A lay-motion for looms, comprising a standard, a fluid-pressure cylinder pivotally mounted thereon, a piston operating in the cylinder and having a pivotal connection with the lay, a connecting-rod also having a pivotal connection with the lay, a rock-lever pivotally mounted on the standard and connected to the connecting-rod, and a dash-pot having its stem in the path of movement of the rock-lever.
20. A lay-motion for looms, comprising a standard, a fluid-pressure cylinder pivotally mounted thereon, a piston operating in the cylinder and having a pivotal connection with the lay, a connecting-rod also having a pivotal connection with the lay, a rock-lever pivotally mounted on the standard and connected to the connecting-rod, a dash-pot having its stem in the path of movement of the rock-lever, and an adjustable stop adapted to be engaged by the stem of the dash-pot to limit the movement of the lay.
21. A lay-motion for looms, comprising a standard, a fluid-pressure cylinder pivotally mounted thereon, a piston operating in the cylinder and having a pivotal connection with the lay, a connecting-rod also having a pivotal connection with the lay, a rock-lever pivotally mounted on the standard and connected to the connecting-rod, a dash-pot having its stem passing entirely therethrough with its lower end in the path of movement of a part of the rock-lever, an adjustable stop adapted to be engaged by the other end of the dash-pot stem to limit the movement of the lay, and a petcock and check-valve connected to the dash-pot.
22. A lay-motion for looms, comprising a fluid-pressure lay-moving device, an electrical controlling means therefor having its circuit-closer formed by a sheet-metal shell secured to the lay-cap of the loom, spring-strips connected thereto, buttons mounted on the spring-strips and projecting through openings in the sheet-metal shell, a strip of insulating material mounted on the sheet-metal shell, and a series of spring-contacts carried thereby.
23. A lay motion for looms, comprising a fluid-pressure lay-moving device, an electrical controlling means therefor consisting of a valve-operating magnet, an electrical circuit therefor containing a relay-switch, and a second electrical circuit including the magnet of the relay-switch and having its circuit-closer located within convenient access to the weaver.

In testimony whereof I affix my signature in presence of two witnesses.
